CLAIM

The ornamental design for an automobile accessory, as shown and described.

DESCRIPTION

FIG. 1 is a perspective view of the first embodiment of an automobile accessory showing our new design;

FIG. 2 is a front view thereof;

FIG. 3 is a top view thereof;

FIG. 4 is a side view thereof, it being understood that the opposite is a mirror image thereof;

FIG. 5 is a bottom view thereof;

FIG. 6 is a top view of a second embodiment of an automobile accessory showing our new design;

FIG. 7 is a perspective view thereof;

FIG. 8 is a front view thereof, it being understood that the rear is mirror image thereof

FIG. 9 is a side view thereof, it being understood that the opposite is a mirror image thereof;

FIG. 10 is a bottom view thereof;

FIG. 11 is a perspective view of a third embodiment of an automobile accessory showing our new design;

FIG. 12 is a top view thereof;

FIG. 13 is a front view thereof, it being understood that the rear side is a mirror image thereof;

FIG. 14 is a side view thereof, it being understood that the opposite is a mirror image thereof;

FIG. 15 is a bottom view thereof;

FIG. 16 is a perspective view of a fourth embodiment of an automobile accessory showing our new design;

FIG. 17 is a top view thereof;

FIG. 18 is a front view thereof, it being understood that the rear side is a mirror image thereof;

FIG. 19 is a side view thereof, it being understood that the opposite is a mirror image thereof; and,

FIG. 20 is a bottom view thereof.

The broken line showing of environment is for illustrative purposes only and forms no part of the claimed design.
